UNITED STATES PATENT OFFICE.

EDWIN B. STIMPSON, OF BROOKLYN, NEW YORK, ASSIGNOR TO EDWIN B. STIMPSON COMPANY, OF BROOKLYN, NEW YORK.

RIVET-FEEDING MECHANISM.

Application filed May 27, 1927. Serial No. 194,630.

This invention relates to rivet feeding mechanism such as used to feed rivets to the operating plunger of a rivet setting machine.

An object of the invention is to provide a mechanism that will feed the rivets smoothly and rapidly without congestion or jamming.

In rivet feeding mechanism now in use the rivet has a tendency to fall over on its side just as it is being fed into the rivet-receiving pocket, and this action causes jamming of the machine. The present invention avoids this difficulty by providing an improved feedway that guides the rivet in such a way that it maintains a position substantially normal to the feedway and hence falls upright into the pocket. This is done by forming the lower end of the feedway with a part of reduced depth that closely engages the head of the rivet and holds it against tilting movement, thereby insuring its proper engagement with the rivet-receiving pocket.

While a preferred form of the invention has been disclosed for purposes of illustration, it should be understood that various changes may be made in the structure without departing from the spirit and scope of the invention as hereinafter set forth and claimed.

30 In the drawings;

Fig. 1 is a plan view of the lower face of a feedway embodying the invention;

Fig. 2 is a section on line 2—2 of Fig. 1;

Fig. 3 is a section on line 3—3 of Fig. 1;

35 Fig. 4 is a section on line 4—4 of Fig. 1; Fig. 5 is a perspective of the cut-off slide.

The device disclosed herein is an improvement on the structure shown in my Patent No. 1,480,577, issued Jan. 15, 1924. In the

40 patented machine the slot for feeding rivets to the holding pocket is of uniform depth throughout its length, and as it must be deep enough to permit free passage of the rivets under force of gravity, the rivet heads fit so loosely therein that they tend to fall over on their sides just as they are leaving the lower end of the feed slot. In

45 the present invention the lower end of the feed slot is of less depth than the main part 50 of the slot, and the rivet head is thus firmly held against tilting as it is being fed to the holding pocket.

Referring to the drawings more specifically, the reference numeral 10 indicates the main part of the feedway in which is formed a T-shaped feed slot 11. A nose piece 12 is secured to the lower end of the feedway, and a cross groove 13 formed in the nose piece receives the cut-off slide 14. Plates 55 15 and 16, which are secured to the nose piece 12, extend over the groove 13 to hold the slide 14 in operating position and carry overhanging flanges 17 and 18 which cooperate to form a continuation of the feed slot 11. 60

Below the groove 13 the plates 19 and 20 are fastened to the nose piece and carry flanges 21 and 22 which cooperate to form a T-shaped delivery slot 23. The flanges 21 and 22 being thicker than flanges 17 and 18, 65 the lateral branches of the delivery slot are of less depth than those of the feed slot, and hence the head of the rivet will fit more snugly in the delivery slot and there will be less possibility for the rivet to tilt. 70

The cut-off slide 14 is formed with a T-shaped slot 24 which is adapted to transfer the rivets from the feed slot to the delivery slot, and the lateral branches of the slot 24 have sloping lower walls, as shown at 25 in 75 Figs. 2 and 5, whereby the rivet heads move from the deep feed slot to the shallow delivery slot.

I claim:—

1. Rivet feeding mechanism including an inclined feedway having a T-shaped feed slot formed therein, a T-shaped delivery slot offset from the feed slot, the lateral arms of the delivery slot being of less depth than those of the feed slot and being of uniform 80 depth throughout their length, and means for transferring a rivet from the feed slot to the delivery slot.

2. Rivet feeding mechanism including an inclined feedway having a T-shaped feed slot formed therein, a T-shaped delivery slot offset from the feed slot, the lateral arms of the delivery slot being of less depth than those of the feed slot and being of uniform 85 depth throughout their length, and a slide for transferring a rivet from the feed slot to the delivery slot. 100

3. Rivet feeding mechanism including an inclined feedway having a T-shaped feed

slot formed therein, a T-shaped delivery slot offset from the feed slot, the lateral arms of the delivery slot being of less depth than those of the feed slot and being of uniform depth throughout their length, and a slide for transferring a rivet from the feed slot to the delivery slot, the slide having a T-

shaped slot therein, the lateral branches of the slot having their lower walls inclined to guide the rivet heads from the deep feed slot to the shallow delivery slot. 10

In testimony whereof I affix my signature,

EDWIN B. STIMPSON.
